UNITED STATES PATENT OFFICE.

WILLIAM N. DURBIN, OF ANDERSON, INDIANA.

TIN-PLATE BRANNING AND CLEANING MACHINE.

Application filed October 18, 1919. Serial No. 331,637.

To all whom it may concern:

Be it known that I, WILLIAM N. DURBIN, a citizen of the United States, and a resident of Anderson, county of Madison, and State 5 of Indiana, have invented a certain new and useful Tin-Plate Branning and Cleaning Machine; and I do hereby declare that the following is a full, clear, and exact description thereof, reference being had to the accompanying drawings, in which like numerals refer to like parts.

The object of this invention is to improve the construction of machines for branning, cleaning and polishing tin plates and effectually removing therefrom the oil, grease 15 or other flux covering the surface of the freshly tinned plates.

Machines of this character have in the front end a set of rolls between which the 20 tin plates pass in succession and a bran box and means for supplying to said rolls and plates bran or other cleaning material, and also a set of cleaning rolls in the rear portion of the machine which receive the tin plates 25 from the branning rolls and are expected to clean the bran or cleaning material from the plates and discharge the tin plates at the end of the machine perfectly free from any of the greasy material or flux and the cleaning 30 material. In these machines heretofore in use, the greasy bran or cleaning material from the branning rolls has been utilized by and carried on to the cleaning rolls in the cleaning end of the machine, with the result 35 that it has been difficult to thoroughly clean the tin plate, for the material utilized by the cleaning rolls at the cleaning end of the machine has not been very clean itself. It has retained the grease and other dirt received 40 from the branning end of the machine. In these machines one hopper has been located beneath both sets of rolls, the branning rolls and the cleaning rolls, and the bran has been discharged therein from the bran box about 45 both classes of rolls and has been elevated and discharged again into the front end of the machine upon the branning rolls and repeatedly used. The result has been that the material soon became filthy and unsatisfactory and the machine had to be stopped 50 and all the branning and cleaning material removed.

Because of the difficulty of cleaning tin plates by said machines, some factories have 55 taken the tin plates issuing from the machine

and carried them to another machine and re-cleaned them. This process is laborious and expensive.

The present machine has for its object the more thorough cleaning of the tin plates, so 60 as to render re-cleaning unnecessary, and also causing a considerable saving in the amount and cost of the bran or cleaning material employed.

The feature of the invention whereby the foregoing object has been accomplished consists in providing a separate supply of bran or cleaning material to the branning rolls and to the cleaning rolls, and to that end each set of rolls in the machine is provided with a hopper, an elevator and a distributor, and the greasy cleaning material in the bran box contained in the branning rolls is not passed or permitted to pass into the cleaning rolls or cleaning end of the machine, but the rolls in the cleaning end of the machine are supplied with an independent supply of clean bran or cleaning material so as to thoroughly clean the tin plates and render re-cleaning quite needless.

The foregoing feature of the invention enables each variety of cleaning material to be used for a longer period than the cleaning material as used in the machines heretofore in use. The greasy bran or cleaning material in the front end of the machine can be repeatedly used until it is in a much greasier and dirtier condition than has even been possible in the old machines, for this material in the present machine is not passed to the cleaning rolls at the cleaning end of the machine. The condition of the bran used in the branning rolls is not very material, as to how greasy or dirty it may be, for it will still effectually rub loose and rub off the grease or 95 flux on the tin plates.

By using relatively clean bran or material with the cleaning rolls at the cleaning end of the machine, which material has not been soiled in the branning end of the machine, 100 not only are the tin plates more thoroughly cleaned, but this bran can be repeatedly used a very long time. It does not become greasy or dirty very fast. The result is not only improved cleaning of the tin plate, but a very 105 material saving in the amount of cleaning material used and a considerably longer use of the cleaning material is rendered possible, and this result is obtained in a single machine driven from a single source of power,

all the rolls of which are arranged in a single series through which the tin plates are continuously passed in succession, the cleaning rolls receiving the tin plates directly from the branning rolls.

The full nature of this invention will be more fully understood from the accompanying drawings and the following description and claims:

- 10 In the drawings Fig. 1 is an elevation of the side of the machine opposite the elevators. Fig. 2 is a perspective view of the machine looking at the elevator side thereof. Fig. 3 is a central vertical section through Fig. 1. Fig. 4 is a central vertical section of the upper part of one of the elevators and the distributor associated therewith. Fig. 5 is a section of parts of the driving shaft and wheels thereon.
- 20 There is shown in the drawings herein a tin plate cleaning machine having a main frame in which the rolls are mounted, consisting of side plates 10 with vertical openings 11 therein for bearing boxes 12 for the 25 rolls and cross partition plates 13, 14, 15, 16, 17 and 18, as seen in Fig. 3. This frame is box-like, open at the bottom and the top however, and is carried and supported by a supporting frame having end legs 19 and 30, longitudinal side bars 21 and 22, straight cross bars 23 and inclined brace bars 24.

Referring to Fig. 3, it is seen that at the feeding end of the machine there is a pair of feed rolls 25, one above the other at the entrance of the branning box or end of the machine. This part of the machine lies between the partition plates 13 and 14 near the front end of the machine and the partition plates 15 and 16 near the middle of the machine. 40 In this branning box there are four pairs of branning rolls 26. Following the branning box and rolls there is a cleaning box located between the plates 15 and 16 near the middle of the machine and the plates 17 and 18 near 45 the end of the machine, and there are seen four pairs of cleaning rolls 27. At the rear or discharge end of the machine to the right hand of the plates 17 and 18, there is a pair of discharge feed rolls 28. These rolls are 50 all arranged so that the bites thereof are in horizontal alignment for the feeding or passage of the tin plates between them through the machine.

The manner of mounting the rolls here shown is not new, the upper bearing box 12 of the upper roll of each pair being forced downwardly by screws 30 so that the rolls of each pair engage each other with such contact as may be desired by the person operating the machine.

The means for driving the rolls in this machine is new in the particular that all of the rolls are driven by sprocket wheels and sprocket chains, and the trouble that has 65 been experienced by the difficulty of accu-

rately making and operating gear driven rolls in machines of the kind heretofore has been overcome and avoided. To that end each roll has a sprocket wheel 31 secured thereon for driving the same, the sprocket wheel on the upper roll, however, being on the opposite side of the machine from the sprocket wheel on the lower roll and the sprocket wheels on the alternate upper rolls

and on the alternate lower rolls are located 75 on the same side of the machine. Therefore, as shown in Fig. 1, on the right hand side of the machine, the first sprocket wheel is on the lower roll of the first pair, the next is on the upper roll of the second pair, the third is on the lower roll of the third pair, the fourth roll is on the upper roll of the fourth pair, and this alternation is carried over to the cleaning box, the fifth wheel being on

the lower roll of the fifth pair of rolls, the sixth wheel on the upper roll of the sixth pair of rolls and so on to the end, while the reverse arrangement is found on the left hand side of the machine, as shown in Fig. 2. This makes two sets of roll driving sprocket

wheels 31, the set on the right hand side all being driven by a single sprocket chain 35 and all of the sprocket wheels on the left hand side of the machine being driven by the sprocket chain 36. Each of these chains

travels over the lower horizontal row of sprocket wheels and under the upper row of wheels, as shown. These two sprocket chains are driven at different rates of speed, and, therefore, the right and left hand sets of

sprocket wheels are driven at different rates of speed with the result that the rolls of each pair are driven at different rates of speed in order to cause the desired rubbing action

of the bran or cleaning material on the tin plates as they pass through the machine. In this particular machine, the left hand sprocket chain 36 and the sprocket wheels and rolls which it drives travel at a slower speed than the other sprocket chain, wheels and rolls. But one roll of each pair of feed

rolls in an idler.

The power for driving the machine is applied to the main driving pulley 40, shown in Fig. 1, mounted on the shaft 41 which extends transversely through the machine. On the left hand end of shaft 41, there is a sprocket wheel 42 secured, which drives the

sprocket chain 43 that runs to the lower rear feeding roll 28, and the lower rear feeding roll drives the sprocket chain 35 on the other side of the machine for operating the fast driven rolls. On the latter side of the machine, see Fig. 1, there is a sprocket wheel

44 secured on the shaft 41 which drives the sprocket chain 45 that runs to a much larger sprocket wheel 46 on the last lower cleaning roll in the machine, and on the other end of said roll there is a sprocket wheel 31 which

drives the sprocket chain 36 at a lower speed

than the sprocket chain 35. The reason for the differential driving of the rolls of each pair is well known in the art.

The partition plates 13 to 18 may be formed substantially as shown, the upper plates 13, 15 or 17 is a plain vertical plate extending down to the middle of the machine with its lower end or lip turned rearward so as to lie slightly above a straight line through the bites of the pairs of rolls, and, therefore, just above the tin plates as they pass through the machine. The lower plates 14, 16 and 18 extend up almost to the upper plates referred to. The lower plates 16 and 18 have their upper lips turned rearward. On the upper partition plates 15 and 17 there are brushes 50 extending down into the path of the tin plates for sweeping off the bran therefrom as they pass out of the bran box and cleaning box respectively.

The bran or cleaning material as it is used in the branning box drops into the hopper 51 below the branning box or front half of the machine and that from the cleaning box drops into the hopper 52 below the cleaning box or rear half of the machine. Said boxes are trough shaped transversely, and in the contracted lower portion of each hopper there is a screw conveyor 53 or 54 respectively with the stub shaft 55 thereof mounted in suitable bearings 56, as shown in Fig. 3.

The screw 53 operates in a screw housing 57 at the left hand side of the machine, as shown in Fig. 2 and discharges into the elevator casing 58 in which an endless bucket elevator 59 is mounted on the shafts 60 and 61. This elevator carries up the bran or cleaning material which screw 53 has taken out of the hopper end of the branning box and elevates it and discharges it into the screw casing 62, which has in it a distributing screw 64 extending across the machine from the first two pairs of rolls in the bran box. By this means the bran or cleaning material is fed or distributed to the branning rolls and upon the tin plates as they enter the machine. The distributing screw 64 is driven by a sprocket chain 66 which leads from the sprocket wheel 166 on the first lower branning roll to a sprocket wheel 67 on the distributing screw, as seen in Fig. 1.

The conveyor screw 54 in the rear hopper under the cleaning rolls or rear half of the machine is mounted in a housing 68, as seen in Fig. 2, and discharges the bran from said last mentioned hopper into a chamber in the conveyor housing 69 at the left hand side of the machine behind the elevator 58. In this housing 68 there is an endless bucket conveyor like the bucket elevator 59, which at its lower end is mounted on the shaft 70 and its upper end on the shaft 71. It discharges into the distributing housing 72, and is conveyed transversely of the machine and is distributed by a screw conveyor 73, similar to

the conveyor 64, upon the pairs of cleaning rolls near the middle of the machine; the last mentioned conveyor 73, as shown in Fig. 1, by a sprocket chain 75 which leads from the sprocket 76 on the first lower cleaning roll to a sprocket 77 on the upper distributing conveyor. The shaft 55 of the lower feed screw 53 is driven by a sprocket wheel 78 thereon and a sprocket chain 79 that extends over a sprocket wheel 80 on the main driving shaft 41, and it also extends about the sprocket wheel 81 on the shaft 55 of the rear screw conveyor 54, as seen in Fig. 3. On the other end of the feed screw 54, as seen in Fig. 3, there is a sprocket wheel 82 secured, which drives a sprocket chain 83 that passes over the sprocket wheel 84 on the lower elevator shaft 60 and the sprocket wheel 85 on the lower elevator shaft 70 and drives those two shafts.

A funnel 86 is secured under the screw casing 62 and 72 and the discharge point of the elevator to which a bag may be attached when it is desired to remove the bran or cleaning material from the hoppers. By withdrawing the slide the bran will be elevated from the hopper and discharged into the bag, whereby it may be removed.

In operating the machine tin plates are fed to the left hand end of the machine, as shown in Fig. 3, and are discharged at the right hand end clean. Since the bran or cleaning material used in the branning portion of the machine does not get into the cleaning portion of the machine, it can be repeatedly used a relatively long time. And for the same reason the bran in the cleaning part of the machine may be used for a long time. When the bran in the cleaning part of the machine needs to be removed, it is usually taken out of that part of the machine and put into the hopper under the branning part of the machine, so that after a long use of the cleaning material in the cleaning part of the machine, it can be used for a long time in the other part of the machine. In this manner the tin plates are very thoroughly cleaned, and there is a great saving in cleaning material.

The invention claimed is:

1. A tin plate cleaning machine including a branning compartment and a cleaning compartment to which the tin plates are fed directly from the branning compartment, means for preventing the bran from passing from the branning compartment to the cleaning compartment, and separate means for supplying cleaning material repeatedly to the branning and cleaning compartments, substantially as set forth, whereby the cleaning material in said two compartments will be kept separate.

2. A tin plate cleaning machine including a branning compartment and a cleaning compartment immediately succeeding the

branning compartment, rolls in said compartments, means for driving the same so that the tin plates will be fed directly from the branning compartment to the cleaning compartment, and separate means for supplying cleaning material repeatedly to the branning and cleaning compartments, substantially as set forth, whereby the cleaning material in said two compartments will be 10 kept, separate.

3. A tin plate cleaning machine including a branning compartment and a cleaning compartment to which the tin plates are fed directly from the branning compartment, 15 means for preventing the bran from passing from the branning compartment to the cleaning compartment, a separate means for feeding the cleaning material from each hopper to its corresponding compartments, whereby 20 the cleaning material in said two compartments will be kept separate.

4. A tin plate cleaning machine having a set of branning rolls, a set of cleaning rolls adjacent the branning rolls in said machine 25 in position to receive the tin plates directly from the branning rolls, means between the branning rolls and cleaning rolls for preventing the cleaning material in the branning rolls from reaching the cleaning rolls, 30 a separate hopper under each series of rolls in position to receive the cleaning material only from its corresponding set of rolls, and separate means for feeding the cleaning material from each hopper to its corresponding 35 set of rolls, whereby the cleaning material in said two sets of rolls will be kept separate.

5. A tin plate cleaning machine having a set of branning rolls, a set of cleaning rolls 40 adjacent the branning rolls in said machine in position to receive the tin plates directly from the branning rolls, means between the branning rolls and cleaning rolls for preventing the cleaning material in the branning rolls from reaching the cleaning rolls, 45 a separate hopper under each series of rolls in position to receive the cleaning material only from its corresponding set of rolls, and elevator associated with each hopper for 50 elevating the cleaning material therein, and a distributor associated with each set of rolls for receiving the cleaning material from its corresponding elevator and supplying the same to its corresponding set of 55 rolls, whereby the cleaning material in said two sets of rolls will be kept separate.

6. A tin plate cleaning machine having a set of branning rolls, a set of cleaning rolls adjacent the branning rolls in said machine 60 in position to receive the tin plates directly from the branning rolls, means between the branning rolls and cleaning rolls for preventing the cleaning material in the branning rolls from reaching the cleaning 65 rolls, a separate hopper under each series of

rolls in position to receive the cleaning material only from its corresponding set of rolls, separate means for feeding the cleaning material from each hopper to its corresponding set of rolls, and a single driving means for driving all of said rolls, and the means for handling and feeding the cleaning material, whereby the cleaning material in said two sets of rolls will be kept 70 separate.

7. A tin plate cleaning machine having a number of rolls arranged in successive pairs for branning and feeding the tin plates passing between, the bites of all pairs of rolls being in horizontal alignment with each other, 80 a sprocket wheel on each alternate lower roll and each alternate upper roll at one side of the machine and on only one roll of each pair, sprocket wheels on the ends of the other rolls at the other side of the machine, so that 85 on each side of the machine there will be two horizontal rows of sprocket wheels, one sprocket wheel being located above and between each pair of lower sprocket wheels, and the sprocket wheels will, therefore, be 90 in staggered relation, a sprocket chain at each side of the machine running over the tops of the series of lower sprockets and under and engaging the series of upper sprockets, and means for driving the sprocket 95 chains at the different sides of the machine at different speeds.

8. A tin plate cleaning machine having a number of rolls arranged in successive pairs for branning and feeding the tin plates passing between, the bites of all pairs of rolls being in horizontal alignment with each other, a sprocket wheel on each alternate lower roll and each alternate upper roll at each side of the machine and on only one 100 roll of each pair, so that on each side of the machine there will be two horizontal rows of sprocket wheels, one sprocket wheel being located above and between each pair of lower sprocket wheels and the sprocket 105 wheels, therefore, being in staggered relation, a sprocket chain at each side of the machine running over the tops of the series of lower sprockets and under and engaging with it a series of upper sprockets, a main 110 driving shaft extending transversely of the machine, sprocket transmission from said shaft to one of said sprocket wheels for causing relatively rapid travel of one roll of each pair of rolls, another sprocket wheel on 115 said driving shaft, a larger sprocket wheel in position to drive the other sprocket chain, a sprocket chain from the last mentioned sprocket wheel on said shaft to said larger chain so that the other rolls of each pair 120 will be driven at a slower speed.

9. A tin plate cleaning machine having a number of rolls arranged in successive pairs for branning and feeding the tin plates passing between, the bites of all pairs of rolls 130

being in horizontal alignment with each other, a sprocket wheel on each alternate lower roll and each alternate upper roll at one side of the machine and on only one roll 5 of each pair, sprocket wheels on the ends of the other rolls at the other side of the machine, so that on each side of the machine there will be two horizontal rows of sprocket wheels, one sprocket wheel being located 10 above and between each pair of lower sprocket wheels and the sprocket wheels, therefore, being in staggered relation, a sprocket chain at each side of the machine running over the tops of the series of lower 15 sprockets and under and engaging with it a series of upper sprockets, a main driving shaft extending through the machine, means driven thereby for driving said two sprocket chains at different speeds, a hopper under 20 the front rolls of the machine, a hopper under the rear rolls of the machine, a screw conveyor in the lower end of each of said hoppers, sprockets on said conveyors, a sprocket on the driving shaft, a sprocket 25 chain from the driving shaft to said last two mentioned sprockets for driving said two screw conveyors, an elevator beside the front part of the machine for elevating the cleaning material from the front hopper, an ele- 30 vator beside the rear part of the machine for elevating the cleaning material from the rear hopper, sprocket wheels and chains for driving said elevators from one of said screw conveyors, a distributor extending trans- 35 versely over the front part of the machine, another distributor over the rear part of the

machine for distributing the cleaning material to the front and rear rolls independently, and means connected respectively with a front and rear roll for driving said distributors. 40

10. A tin plate cleaning machine including a branning compartment and a cleaning compartment to which the tin plates are fed directly from the branning compartment, 45 and means for supplying cleaning material to the cleaning compartment independently of the branning compartment.

11. A tin plate cleaning machine including a branning compartment and a cleaning 50 compartment, rolls in the cleaning compartment to which the tin plates are fed directly from the branning compartment, and means for supplying cleaning material to the rolls in the cleaning compartment independently 55 of the branning compartment.

12. A tin plate cleaning machine including a branning compartment and a cleaning compartment, rolls in the cleaning compartment to which the tin plates are fed directly 60 from the branning compartment, means for preventing cleaning material from passing from the branning compartment to the cleaning compartment, a hopper to receive the cleaning material from only the cleaning 65 compartment, and a conveyor for elevating said cleaning material from said hopper and discharging the same upon the rolls in the cleaning compartment.

In witness whereof, I have hereunto af- 70 fixed my signature.

WILLIAM N. DURBIN.
